UNITED STATES PATENT OFFICE.

CLARENCE HEISEY, OF NEWARK, OHIO, ASSIGNOR TO A. H. HEISEY & CO., OF NEWARK, OHIO.

DESIGN FOR A GOBLET OR SIMILAR ARTICLE.

46,733.

Specification for Design.

Patented Dec. 8, 1914.

Application filed April 28, 1914. Serial No. 835,044. Term of patent 7 years.

To all whom it may concern:

Be it known that I, CLARENCE HEISEY, a citizen of the United States, residing at Newark, Ohio, have invented a new, original, and ornamental Design for a Goblet or Similar Article, of which the following is a specification, reference being had to the accompanying drawing, forming part thereof.

Figure 1 is a side elevation of a goblet illustrating my new design. Fig. 2 is a cross section taken through the stem of the goblet. Fig. 3 is a cross section taken through the main body of the goblet.

The characteristic features of this design are the parallel, vertical panels which merge into the stem and base of the goblet, the outer faces of these panels being concave and the inner wall of the goblet cylindrical.

I claim:

The design for a goblet or similar article, substantially as shown and described.

CLARENCE HEISEY.
